REVERSIBLE DRAWSTRING HANDBAG

Joseph Cohen, New York, N. Y., assignor to James Arden, New York, N. Y.

Application March 7, 1950, Serial No. 8,376

Term of patent 3½ years

(Cl. D87—3)

To all whom it may concern:

Be it known that I, Joseph Cohen, a citizen of the United States, and a resident of New York, in the county of New York and State of New York, have invented a new, original, and ornamental Design for a Reversible Drawstring Handbag, of which the following is a specification, reference being had to the accompanying drawing forming a part thereof, wherein:

Fig. 1 is a perspective view of a reversible drawstring handbag embodying my new design, with the handbag in open condition;

Fig. 2 is a perspective view thereof in closed condition;

Fig. 3 is a side elevational view of the handbag as shown in Fig. 1, a corner of the collar or ruffle element being turned back; and

Figs. 4 and 5 are perspective views corresponding to Figs. 1 and 2 respectively, illustrating the handbag reversed.

The figures of the drawing are stippled and cross-hatched to indicate contrast.

My design for a reversible drawstring handbag resides in the triangular ends combined with the rectangular sides in association with the contrasting collar along the top of the handbag, said collar overlapping the sides of the handbag and contrasting therewith in either reversed position of the handbag.

I claim:

The ornamental design for a reversible, drawstring handbag, substantially as shown and described.

JOSEPH COHEN.
